UNITED STATES PATENT OFFICE

ROBERT F. CAMPBELL, OF MIAMI, FLORIDA

HEATING-CONTROL ATTACHMENT FOR HOT-WATER BOILERS

Application filed July 29, 1928. Serial No. 125,772.

Almost without exception dwellings are provided with domestic hot water boilers, and in many instances the heating medium to heat the water in such boilers is gas or electricity, which medium has no alarm or check, but the house-holder depends entirely on his memory to remember to turn off the current or other heating medium when sufficient water has been heated. The experience of the average 5 householder is that in the majority of cases he forgets to turn off the heating medium whereby heat is wasted and the expense of maintaining the hot water supply materially and unnecessarily increases.

10 The object of my invention, broadly stated, is to provide an attachment for domestic hot water boiler which can be secured to any standard boiler and so positioned on the boiler as to control the percentage of volume of 15 water to be heated in the tank. That is to say, if one requires but ten gallons of hot water the attachment can be so adjusted on the boiler that the supply of the heating medium is automatically cut off after ten gallons have been 20 heated. In some instances it may be cheaper and desirable to operate an alarm instead of cutting off the heating medium after the pre-determined amount of water has been heated 25 in the boiler. This, of course, is optional and 30 controlled by the circumstances of each installation.

35 My invention consists, broadly stated, of an attachment adapted to be adjustably secured to the outside of a domestic hot water tank, said attachment carrying a heat responsive mechanism in contact with or close proximity to the outer face of the hot water boiler, said heat responsive mechanism being suitably 40 connected with the switch or an alarm.

In the drawings:

Figure 1 is a front elevation of a domestic hot water boiler partly in section with my invention in an adjustable position thereon.

45 Figure 2 is a detail sectional view of my invention with a solenoid in the circuit.

Figure 3 is a diagrammatic view illustrating my invention with a ball circuit.

50 The reference numeral 1 designates a domestic hot water tank or boiler which may be

of any approved construction and of any desired capacity.

My improved attachment for hot water boilers consists of a ring 2 which is adapted to be adjustably secured at any point between the top and bottom of the boiler by means of a set screw, or other suitable device 3. A suitable case 4, preferably made of aluminum is secured to the ring 2 by means of the set screws 5 which enter suitable recesses in the cup or case 4. This cup or case 4 may be made with one of its side walls concaved to conform to the perimeter of the tank 1 as will be readily understood, whereby a materially larger area of contact is afforded between the wall of the tank 1 and the cup 4. A case or cup 4 is provided with a cap or cover 6 which may also be made of aluminum and have one of its side walls concave to conform with the concave wall of the cup 4. This cap has flanges 7 which project down in the case 4 and rest snugly on top of the shoulders of the mercury tube 8 which is seated in the case or cup 4. If desired or if thought necessary, a suitable pad may be placed on the shoulders of the mercury tube to prevent the flange 7 of the cap 6 from damaging the tube, yet holding the tube snugly and firmly in place by the cover. The cap 6 is provided with a screw thread opening in which is adjustably seated a contact screw 9. This screw is properly adjusted relative to the mercury tube so as to complete a circuit when the mercury is expanded. The cap 6 is securely fastened to the cup or casing 4 by means of a screw 10. In this connection it will be noted 85 that the contact screw 9 is not insulated from the aluminum cap 6.

Take for example a forty gallon tank 1 and assuming that only ten gallons of hot water are necessary or desired, the band 2 with the 90 cup 4 and its associate parts are adjusted to a point from the top about one-fourth the length of the tank, secured in that position after which the heating medium is turned on and in the case of an electric current the circuit will function as follows:

When the hot water inside of the tank 1 reaches down as far as a point opposite the mercury tube 8 the heat from the water passing through the metal wall of the tank 1 will 100

be conveyed to the mercury tube 8 and the mercury will expand and make contact with the said screw 9, then we have a circuit from the battery 11 through the bell 12, lead 13 to cover 6 and set screw 9, the set screw 9 not being insulated from the cover 6, the current will pass down through set screw 9 which due to the expansion of the mercury is making contact with the mercury, the current going through the mercury to lead 14 (which is in direct contact with the mercury at all times, but is securely insulated where it passes through the cup 4) and back to the battery which will complete the circuit and cause the bell to ring giving notice that the required amount of water has been heated.

When an electric current is to be used for heating the water the switch 15 will be designed to function on the same control which 20 operates the switch controlling the heating filament 17. In this way the alarm will be set at all times that the heating current is passing through the filament. Of course, it will be understood that the two switches are to be 25 carefully insulated from each other so that the two electric circuits will have no connection, but at the same time the same knob 16 or lever that operates one will also operate the other.

30 Such an arrangement of the two switches will insure the setting of the alarm at all times that the water is being heated, and will facilitate the opening of the alarm circuit when it is not being used.

35 The size and shape of the mercury tube 8 will vary depending on the sensitiveness desired.

Referring to Figure 2: Pushing the solenoid 15' down makes contact at 18 and when 40 heat expands mercury 8' to contact with screw 9' the circuit is complete through the lead 13' and bell 12' back to solenoid 15'. After there is contact between the mercury and the contact screw 9' the pawl or other 45 similar device 19 holds the solenoid plunger 20 in elevated position out of contact with the contacts 18. By this wiring the alarm 12 is first sounded after the predetermined amount of water has been heated after which 50 the solenoid core is elevated and the circuit broken. The user of the attachment then will disconnect the pawl 19 from the solenoid core 20 and restore the system to operative position.

55 In Figure 3 I have shown my invention specially adapted for use in connection with the commercial gas heater and from the description given in connection with the other figures it is thought that the operation is obvious. In Figure 3, 21 is the gas heater. The bell circuit shown in Figure 3, it is believed, is so simple that no description is necessary for the same.

What I claim is:

65 An attachment for domestic hot water

boilers to control the percentage of volume of water to be heated in said tank, comprising a ring adjustably secured to the boiler by a set screw, a case carried by said ring and having one of its sides concaved to conform to the 70 surface of the boiler, a cap for said case, one edge of which is concaved to fit the boiler, flanges depending from the cap into the casing, a mercury tube in the casing with which said flanges contact, a contact screw carried 75 by the cap coating with the mercury, and electric circuit controlling means including said screw and governed by expansion and contraction of the mercury.

In testimony whereof I affix my signature. 80
ROBERT F. CAMPBELL.
